CLAIM

The ornamental design for a data entry writing pad for
electronic filing system, as shown and described.

DESCRIPTION

FIG. 1 is a top plan view of a data entry writing pad for
electronic filing system showing my new design;

FIG. 2 is a bottom plan view thereof;

FIG. 3 is a bottom, front perspective view thereof;

FIG. 4 is a rear elevational view thereof;

FIG. 5 is a right side elevational view thereof;

FIG. 6 is a left side elevational view thereof; and

FIG. 7 is a top, front, right side perspective view
thereof.
